MOBILE DINER

Al N. Zale, also known as Al N. Zalewski,
12471 Zigzag Way, Tustin, Calif.

Filed July 1, 1960, Ser. No. 61,195

Term of patent 14 years

(Cl. D14—3)

The dominant features of the design reside in the portions shown in full lines.

I claim:

The ornamental design for a mobile diner, substantially as shown and described.
